UNITED STATES PATENT OFFICE.

CHARLES F. KETTERING, OF DAYTON, OHIO, ASSIGNOR TO GENERAL MOTORS RESEARCH CORPORATION, OF DAYTON, OHIO, A CORPORATION OF DELAWARE.

AIR-COOLED ENGINE.

Application filed April 17, 1922. Serial No. 553,938.

This invention relates primarily to improvements in direct air cooling systems for internal combustion engines.

This invention is a division in part of my copending application Serial No. 514,014, filed November 9, 1921.

One of the main objects of the present invention is to provide a direct air-cooling system for internal-combustion engines especially suitable for automobiles in order that such engines when employed upon automobiles will give a relatively high fuel economy, and may be operated at relatively high compressions without the objectional fuel knock which has heretofore operated to prevent the general commercial adoption of air-cooled engines.

In carrying out the aims of the present invention there is provided an engine, the cylinders of which have attached thereto a number of radiating fins of a metal of high conductivity, the attachment of said fins to the cylinders being such that the heat generated in the engine cylinders can readily flow into the fins, the faces of which are preferably located in the path of a stream of cooling air which may be provided by means of a suitable fan. In the preferred embodiment of the present invention hereinafter described, the cylinders are constructed in accordance with the inventions contained in the copending application referred to. In carrying out the invention there is provided an internal combustion engine of the air cooled type operating at compression pressures in the cylinder which are higher than those generally utilized in commercial air cooled engines, and are as high and even higher than the compression pressures which are obtained in water cooled engines of the type generally utilized today in commercial automobiles.

A further object of the invention is to provide an internal combustion engine having a cylinder with high conductivity fins bonded thereto, the dimensions of these fins being predetermined, to secure a sufficient efficiency of operation of the engine, and if desired to permit the engine to operate at maximum efficiency with an employment of the minimum amount of copper.

A further object of the invention is to provide an air cooled internal combustion engine having a high compression in which the number and dimensions of the high con-

ductivity fins and the volume of air which flows over said fins is predetermined to permit the engine to operate at substantially full load without "knocking."

A still further object of the invention is to provide an air cooled internal combustion engine in which the engine operates at high compression pressures without knocking and in which the relation of the fin dimensions to the air propelling means is so predetermined that the air propelling means absorbs only a relatively small horse power from the engine for its operation.

Further objects and advantages of the present invention will be apparent from the following description, reference being had to the accompanying drawings, wherein a preferred embodiment of the present invention is clearly shown.

Fig. 1 is a plan view partly in section of an engine embodying the present invention shown mounted in an automobile frame, a fragment of which is shown;

Fig. 2 is a side elevation partly in section of the engine shown in Fig. 1;

Fig. 3 is a front view thereof;

Fig. 4 is a plan view of one of the engine cylinders shown in Fig. 2;

Fig. 5 is a side elevation thereof;

Fig. 6 is a bottom view thereof;

Fig. 7 is an enlarged sectional view of a fragment of the cylinder and fin structure prior to bonding the fins to the cylinder shell;

Fig. 8 is a side view of a cylinder and draft tube assembly the fins being equal in height;

Fig. 9 is a cross sectional view taken through the line 9—9 of Fig. 8; and

Fig. 10 is an enlarged view of a diagrammatic and exaggerated nature showing in cross section the bond between the fins and the cylinder wall.

Referring to Figs. 1 to 6 of the drawings the engine 200 which embodies the present invention is more completely described and illustrated in the copending application of Charles F. Kettering and Charles R. Short, Serial No. 553,938, filed April 17, 1922, which has matured into Patent No. 1,644,731 of Oct. 11, 1927. In order to understand the present invention the following brief description of this invention is given:

The engine 200 includes a crank case 203 having its bottom closed by oil pan members 110

700 and 701, and a plurality of cylinders 220, 221 supported by the crank case 203.

In the engine shown there are 6 cylinders arranged in pairs each pair consisting of cylinders 220, 221. One of the cylinders 221 is shown in detail in Figs. 4, 5 and 6. Cylinder 221 includes a horizontal base portion 222, a relatively thin vertical shell portion 223, and the thicker head portion 224. The base portion 222 is formed with openings 225 for receiving a part of the valve mechanisms, and with holes 227 through which bolts may pass for securing the cylinders to the crank case. The groove 231 shown in Fig. 6 receives packing material in order to secure a tight joint between the cylinder base and the crank case.

The cylinder shell 223 has a vertical outer surface to which are attached a plurality of fin loops 237 which are briefly constructed of a continuous strip of thin relatively pure copper or other material of high heat conductivity. The method and apparatus for constructing these fin loops are described and claimed in the copending application of Charles L. Lee, Serial No. 478,793, filed June 20, 1921, now Patent No. 1,507,318 of Sept. 2, 1924, and the manner of attaching the fins to a cylinder is described and claimed in my copending application Serial No. 514,014, to which reference has been made. These fins are not all of equal height as shown in Figs. 4, 5, 6, those on the left-hand side of the cylinder being shorter than those surrounding the portions of the cylinder shell and the fins in the right-hand side of the cylinders, being shortened slightly. This arrangement of the finning permits a close grouping of all of the cylinders and facilitates the placing of the cylinders in pairs as shown in Figs. 1 and 2 with an intake pipe for a pair of cylinders. This arrangement of finned cylinders is more particularly described and claimed in my copending application Serial No. 417,095, filed Oct. 15, 1920, now Patent No. 1,489,324 of April 8, 1924. The lower ends of the fin loops are provided with vertical slots 238 to permit cleaning dust and other foreign material from the inside of the loops by means of a narrow brush whose bristles project through the slots.

Each cylinder head 224 is provided with intake and exhaust ports 239 and 240, respectively, and with a hole 245 tapped to receive a spark plug 246, and with tapped holes 247 to receive bolts or the like for securing a superstructure 250 to a pair of cylinders.

The cylinder superstructure designated as a whole by numeral 250 is secured to the heads of each pair of cylinders 220 and 221, and includes a common intake 253 for a pair of cylinders, said intake having branches 254 and 255, communicating with

the intake ports of cylinders 220 and 221, respectively. 256 and 257 are exhaust conduits leading respectively from the exhaust ports of the cylinders 220 and 221. Each superstructure 250 supports intake and exhaust valves which are actuated by rocker arms 274 and 275 mounted on a rod 273 which in turn is carried by brackets, 271 and 272 formed integrally with the superstructure 250. These rocker arms 275 and 274 are actuated by push rods 288 which are moved upwardly by a timing mechanism not shown. Springs 264 normally retain engine valves upon their seats.

Fan belt driving pulley 808 is operated by the engine and drives through fan belt 810, a fan pulley 835 which drives fan 820 mounted upon a shaft 812 one end of which is supported by bracket 811 attached to the engine crank case, and the other end of which is carried by the fan spider 813 which in turn is supported by the engine superstructure 250 as shown in Fig. 2. The belt 810 is of the type as will give high efficiency without being drawn taut on the pulley wheels as in prior practice thus reducing the pressure and power required to drive the fan. The power required for driving the fan is also reduced by employing a fan of the peripheral discharge type having a large intake and discharge throat which will give the fan a large capacity, the air being drawn out readily at a relatively low velocity. The fan 820 includes a fan outer wall 838 having an inwardly projecting center conoidal portion for deflecting the air entering the fan up toward the blades 839 which are supported between the fan outer wall 838 and the fan inner wall 840. This inner wall 840 has a rearwardly extending annular flange 841 which extends within the flange 814 of the fan spider 813. A plurality of spider arms 816 serve to connect the flange 814 with a fan shaft 812 and with a mounting pad 817 which is bolted directly to the superstructure 250. The rotation of the fan is clockwise as viewed in Fig. 3, and the blades 842 are so arranged as to push the air out of the fan with such pressure as to overcome the atmospheric pressure surrounding the fan but at the same time without imparting to the fan exhaust a velocity which has a substantial effect on the efficiency of the cooling system.

The draft tube shown in Figs. 1 and 2 is designated as a whole by numeral 850 and comprises three principal sections 851, 852 and 853. Sections 851 and 852 have bottom walls 854 and 855 respectively which project inwardly from side walls 856 and 857 respectively. These bottom walls 854 and 855 are scalloped so as to fit around the cylinder fins and these bottom walls support skirt members 858 and 859 respectively. The wall 856 of member 851 supports a fixed tapered

draft tube portion 862 which cooperates with a movable tapered draft tube portion 853 to provide a housing for the superstructure and valve mechanism and to provide a tube for 5 conducting the cooling air to the circulating fan. Cover 853 is hinged at 863 so that the cover may be swung to one side to give access to the tube portion of the engine. When in position the cover 853 is secured by 10 means of bolt members 864. These draft tube portions extend toward the front end of the engine to the fan spider 813. The draft tube 850 is attached to the engine superstructure 250 by means of the T bolt 15 members 889 and the clamps 892 which likewise secure the manifolds 870 and 871 to the superstructures, it being understood the dowel sleeves which connect the branches of the manifolds 870 and 871 with the various 20 253, 256 and 257, pass through apertures in the vertical wall 856.

The engine crank case 203 is provided with arms 206 and 207 by means of which the engine is supported upon brackets 208 and 25 209 forming the part of the automobile frame. These brackets 208 and 209 support frame members 213 and 214 respectively, which are connected at their free ends with a cross member 212 which assists in supporting the front end of the engine.

I will now proceed to describe the construction of the fins and their attachment to the cylinder walls. Referring more particularly to Fig. 7 it will be seen that the fins are 35 formed from a strip of copper bent or crimped to the shape of the fins and in the embodiment here illustrated I have shown all the fins made from a continuous thin strip of copper. These fins are attached to 40 the cylinder simultaneously and have their uniform treatment; that is, each fin is subjected to substantially the same condition as all the other fins in the process of attaching the fins to the cylinder. The preferred process 45 of attaching said fins to the cylinder is fully described in my copending application, Serial No. 514,014, filed November 9, 1921, and I shall not refer in detail to said process of manufacture herein other than to state 50 that it involves the brazing of the fins to the cylinder walls by means of brazing metal such as brass or silver solder, and in the preferred form of said process for attaching the fins to the engine cylinder, a band of brazing 55 brass 34, Fig. 7, is interposed between the faces of the fins and the cylinder wall 30. An iron wire 35 is tied around the assembly 60 of fins and cylinder, and the assembly is placed in a suitable furnace. Owing to the difference in the coefficient of expansion of the copper fins and the iron of the iron wire 35, the fins are pressed against the bonding metal 34 during the heating operation, and an intermingling, alloying, union or penetration 65 of the metal takes place during the

heat treatment as fully described in the said copending application.

The fins are preferably made of substantially pure metallic copper and it is preferred that this sheet of copper should be of 70 uniform gauge, and while the thickness of the copper depends upon the type of engine upon which it is employed and the other factors, I prefer to have an engine for only pleasure car purposes to employ fins made 75 of a thin sheet of copper.

It will be noticed with reference to the drawings that in Figs. 1 to 6 the fins are of unequal height while in Figs. 8 and 9 is illustrated a construction in which the fins are of 80 uniform height. For purposes of convenience I term the "finning" illustrated in Figs. 1 to 6—eccentric finning, and the "finning" illustrated in Figs. 8 and 9—concentric finning. The purpose of the eccentric finning is to permit of bringing the engine cylinders more closely together as more particularly described in my copending application, Serial No. 417,095, above mentioned. 85

Referring to Figs. 1 to 6 it will be noted that the finning structure when assembled on the cylinder presents a configuration which is substantially eccentric with respect to the periphery of the shell notwithstanding 90 the fact that the faces of the fins are concentric with and attached to the shell. The finning structure consists of a plurality of fin loops 32, each loop including two fin portions exposed on both surfaces to cooling 100 air and of base portions 33 connecting the lower loops 32. The distance from the base of the fin to the outer end of the fin is herein-after referred to as the height H of the fin; the distance from the top edge of the fin to 105 the bottom edge of the fin in a longitudinal direction is referred to as the length L of the fin; the distance between the center line of each fin loop and the center line of the adjacent fin loop is called the pitch P of the 110 fin (see Fig. 7). It will be noted with reference to Fig. 7 that the faces of successive fins are contiguous to each other, thus forming approximately a circle and as a result of the process of manufacture of said fins as 115 described in my said copending application, Serial No. 514,014, these base portions follow the periphery of the cylinder and preferably form an encasing skin of metal around the entire outer periphery of the 120 cylinder shell thus forming extremely efficient heat conducting bond for attaching the fins to the cylinder. The nature of this bond will be understood more particularly with reference to Fig. 10 in which 145 represents 125 a cast iron cylinder and 146 represents the zone of intermixture alloying or adhesion between the iron and the brazing solder, 147 represents the zone of solder, 148 represents the zone of intermingling, alloying or ad- 130

hesion between the solder and the copper of the finning structure, and 149 represents the substantially pure copper. The zones 146, and 148, are represented diagrammatically by the symbols α and may not be as thick, relatively, as the drawing indicates. So far as I am able to ascertain I believe that these zones are present in the completed structure. But the dimensions and thicknesses are exaggerated for the sake of clearness, and are not intended to be accurately proportional. Microphotographs of sections of bonds produced by the herein-described process seem to indicate that there is a progressive merging metallic path for the conduction of heat from the iron to the copper, and tests tend to show that true thermal connection exists between the fins and the iron. At least this union offers considerably less resistance to the passage of heat than would be the case in a junction where the copper fins are merely in contact with the iron.

It will be noted from examination of Fig. 10 that the brazing solder has flowed up between the edges of adjacent fins during the brazing operation as indicated at 150, bonding these fins together, thus strengthening the roots of adjacent fins. The bases of adjacent fins are thus each interconnected by the brazing solder alloyed therewith so that there is formed a continuous "skin" of heat conducting metal around the outside of the cylinder from which the roots of the fins project and merge into the fins proper, the roots of these fins being preferably of greater thickness than double the thickness of the fins beyond the roots.

While it is desirable to have a continuous skin on the outside of the cylinder, as described above, as it permits of equalizing the distribution of heat in the outer surface of the cylinder, the invention is not limited to a bond between the fin and the engine cylinder which results in the formation of a "skin," as each fin might be affixed by a bond of the type described above without contacting with the adjacent fins. Moreover the contact between each fin and the engine cylinder may be and preferably is continuous it may also be a series of short contacts. It will be noticed that the flow of heat takes place very readily from the inside of the cylinder shell to the fins; a relatively thin iron shell is preferably used, and the heat passes rapidly to the bond and passes relatively unimpeded over the zones 146, 147 and 148 into the copper 149 of the fins which are usually subjected to cooling air as hereinbefore described. The melting point of the brazing metal being higher than that attained in the normal operation of the engine, there will be no tendency for the fins to come off the cylinder in the operation of the engine due to the heat of engine operation, and tests extending over a considerable

period indicate that no deteriorating action tending to weaken the bond takes place after rapid running of the engine for a considerable length of time, so that the attachment of the fins to the cylinder may be termed a permanent one. It will be found that the union between the fins and the engine cylinder is continuous not only circumferentially between adjacent fins, but also longitudinally between the shell and the fin. The mechanical strength of this union is such that if it is attempted to pull the fins off the cylinder of the dimensions heretofore described, they will break at a point in the copper and not at the point of junction.

It will further be noticed that a large number of copper fins are employed, and that these fins are made of relatively thin copper; each fin is permanently attached to the cast iron cylinder by the intermediary of a heat conducting union which covers an extensive area of the cylinder compared with the cross sectional area of the fin.

Good results have been obtained by the use of a fin in which the height of the fin is in the neighborhood of about 70 times the thickness of the metal of the fin; the total number of fins employed and their height and length and distance apart are also preferably predetermined with the view to providing a very extensive heat dissipating surface. This extensive radiating surface is obtained by employing a large number of thin copper fins separated by relatively small air spaces.

While the union of metals in accordance with the invention may be employed with any thickness of copper fins, I prefer nevertheless to use it with a thin fin such as described herein, and having the advantages referred to.

It will be noted by examination of the strip of finning illustrated in Figs. 7 and 9 that the fins are equidistantly separated and are folded so as to have the inner edges provided with a flat base produced by "flaring" the inner portions of the several folds or crimps as clearly shown. This form of fin, which may be termed a "flare edge" or "base-formed" fin, has been found to have decided advantages. It assists in uniformly spacing the fins apart, and it provides for more equal distribution of the air between the fins.

The preferred form of fin or cooling element consists of a fold or fin loop of sheet metal forming a flattened tube having one edge attached to the cylinder wall. This tube is open at both ends and allows the passage therethrough of a draft of air, while an additional draft of air is caused to pass along the outside of the several fins by surrounding the entire fin structure with a draft tube or skirt as heretofore described with reference to Figs. 1 and 2.

Owing to the fact that as described in the process of the aforesaid application, Serial No. 514,014, the complete finning structure is united with a cylinder in a single bond 5 operation, it follows that each fin is attached to the cylinder by substantially the same amount and thickness of bond metals and the same kind of bond made under exactly the same conditions as its neighbors in other 10 words, the fins are uniformly attached to the cylinder, and this makes uniformity of the flow of heat into the fin in the running of the engine. The bond between the fin structure and the cylinder is substantially 15 the same irrespective of whether the finning is eccentric or concentric; in the case of the eccentric finning shown in Figs. 1 to 6 the finning is shortened at the points where the cylinders of a pair are arranged in proximity with one another. By arranging the 20 cylinders in pairs with the inlet ports of the cylinders adjacent to one another, it becomes possible to reduce the height of the fins between each cylinder of a pair, as said 25 cylinders are cooled on the inlet sides thereof by the incoming fuel mixture. In referring hereinafter to the dimensions of the fins in connection with the concentric finning I shall refer to the height H of the fins as indicating 30 the normal height, such as the height of the majority of fins and not the height of those fins which have been shortened to permit the engine cylinders to be positioned close together or to permit the passage of 35 valve rods 228.

Special dimensional factors.

It is among the objects of the invention to provide an air cooled internal combustion engine which will run at a very high efficiency, and when used in an automobile vehicle, will give a high mileage per gallon of gasoline or other fuel employed. It is well known that the greater the compression of the engine 45 (within practical limits) the greater the efficiency of the engine from the standpoint of power, and fuel economy. The maximum practicable compression for a given commercial fuel depends upon the temperature of the engine cylinder, and with the ordinary grades of commercial fuel at present in use in the United States, and the ordinary water cooled engine at present in use, the compression pressures in the engine cylinders 50 range from about sixty-five pounds to the square inch to as high as ninety pounds to the square inch for automobiles; engine compression pressures of sixty-five pounds are referred to as low compression pressures, and a compression pressure of ninety pounds 55 would be referred to as a very high compression pressure for vehicle engines, although compression pressures considerably higher have been employed in airplane engines, said pressures for airplane engines going as high as 125 pounds to the square inch. But it must be remembered that such engines must employ a special grade of fuel, such as a high grade gasoline which is not generally commercially obtainable all over the country. 70 It is common in water cooled engines to utilize an engine compression of about 75 pounds to a square inch or under, although in a minority of cases a higher compression pressure is employed in the cylinders. 75

I have so constructed the present air cooled engine that it can operate with compression pressures at least as high as 75 pounds to the square inch, and at compression pressures which are considerably higher than this average compression pressure of 75 pounds of commercial water cooled engines employed in automobiles at the present time for operation upon ordinary commercial fuels. 80

Air cooled engines at present in commercial use for automobiles have generally operated at relatively low compression pressures and considerably below 75 pounds to the square inch; any attempt to exceed said compression pressure would be accompanied by extremely objectionable "knocking" and overheating in the running of the automobile. 85

The cooling system of my improved internal combustion engine is designed to so reduce the cylinder temperatures that the compression pressure can be carried considerably higher than has heretofore been obtained in air cooled engines without extremely objectionable "knocking," thereby resulting in a far more efficient air cooled engine than has heretofore existed. An automobile which is impelled by my new air cooled engine can therefore take hills 90 at full load with little objectionable knocking, notwithstanding its high compression pressure, and in addition such an automobile has the advantage of running at a high mileage per gallon of gasoline as compared 95 with an automobile driven by the usual low compression air cooled engine. 100

The extent to which the temperature of the cylinder can be lowered and the compression increased generally depends upon the following main factors; the number and dimensions of the copper fins; the amount of air passing over the fins; also the relation of the number and dimensions of the fins 105 to the amount of the air passing over them. The number of fins is generally limited by the peripheral area of the cylinder and the thickness of the copper employed; and the dimensions of the fins are governed in part 110 by the conductivity of the copper and other factors hereinafter described. The amount of air flowing over the fins is limited by the power required to drive the fan, inasmuch as therecomes a time when so much power is 115 required to drive the fan to get increased 120

cooling that the useful power developed by the engine is diminished owing to the power absorbed by the fan.

I find it desirable to provide as many fins as possible per linear inch of the periphery of the cylinder; I have found that excellent results are obtained when there are from 10 to 13 fins per linear inch of the periphery of the cylinder. I also find that very good results are obtained with a fin the height of which is about $1\frac{1}{2}$ inches, although practical considerations may prevent the employment of a fin of such height in automobile engines. Good results have actually been obtained with fins having a height of between $1\frac{1}{8}$ to $1\frac{1}{4}$ inches, although of course I do not in any way limit myself to these dimensions, as they could be considerably less or more, as my invention is not in any way limited to any particular dimension of fins.

The thickness of the metal employed in the fins may be determined by a number of considerations, but I find it desirable to maintain a substantially definite ratio between the height and thickness of the fin. I prefer this ratio to be in the neighborhood of between 45 to 80; that is the height H of the fin will be between 45 to 80 times the thickness T .

The length of the fin is preferably determined by the distance between the fins. If the fin length is too great relative to the distance between the fins, the air passing between the fins may become saturated with heat before it has completely passed over the entire length of the fins. I find that good results are obtained by my improved fins when the length of the fins are made as long as possible, the length being limited by the length of the cylinder, but I prefer that this length should not be greater than between the neighborhood of 60 to 80 times the distance between the fins, a practical length being apparently about 70 times the distance between the fins.

The amount of air flowing over the fins is limited by the power that can be efficiently employed for driving the fan, for while it is true that the greater the flow of the air stream, the lower the temperature will be, and the greater the compression of the engine can be made, there comes a time when the power employed to lower the temperature in this manner is greater than the power gained as a result.

I prefer to predetermine the air propelling means or fan with relation to the cooling fins so that the air propelling means or fan absorbs only a relatively small horse power from the engine for its operation; in other words, my improved structure and dimensions as hereinabove described enable the engine to run at relatively high compression with the utilization of a fan which ab-

sorbs only a small amount of power of the engine. In actual practice I prefer to use a fan the horse power of which is equal to about from 1 to 3 per cent of the total brake horse power of the engine.

I have secured excellent results with a 6-cylinder engine substantially as illustrated herein having finning with the following dimensions:

Bore of cylinder $2\frac{1}{8}$ inches;

Stroke of cylinder $4\frac{3}{4}$ inches;

Number of copper fins 116;

Height of fins $1\frac{1}{8}$ inches;

Length of fins 6 inches;

Thickness of fins .015 inches;

Compression pressure in engine cylinder, about 80 pounds; and spacing between the fins about 12 or 13 to the inch.

The fan employed, which is of the construction illustrated in the drawing, absorbs about $1\frac{1}{2}$ per cent of the brake horse power of the engine.

I prefer to use a very large number of copper fins, and usually about 12 to 13 to the inch. For ordinary commercial uses, there will generally be over 100 fins to a cylinder; for instance in a small cylinder having a bore of $2\frac{1}{2}$ inches and a stroke of 3 inches, I have actually used 104 fins with good results; in a 4-cylinder engine having a bore of $3\frac{1}{2}$ inches and a stroke of $3\frac{1}{2}$ inches, I have used 116 fins with good results. In a large bore engine suitable for tractor purposes with a bore of $4\frac{3}{4}$ inches and a stroke of $4\frac{3}{4}$ inches, I have actually used 175 fins.

It will be noted that the fan is driven from the engine by a driving connection which permits it to be driven faster than engine speed; therefore the capacity of the fan is not limited by the speed of the engine. This makes the capacity of the fan independent of the engine speed to the extent that the fan can be driven at the correct speed for the allotment of power for the fan; in other words, as compared with the case where the fan is in the engine flywheel (as is common practice) and must necessarily rotate at the same speed as the engine, I am enabled to make the fan work more nearly in proper relation to the cooling system as a whole, than in the case where the fan is in the flywheel.

While I have described herein a satisfactory form of internal-combustion engine which embodies my invention and have presented preferred dimensions which I have found to give good results, I wish it to be clearly understood that the description of the preferred embodiment and said dimensions herein are given by way of example only, as I believe that the internal-combustion engine of the present invention comprises features which are inherently and apparently broadly novel, since I believe

that I am the first to provide an internal-combustion engine in which a plurality of copper fins are attached to a cast iron or other type of cylinder by a metallic union which is permanent, gives excellent thermal contact, is mechanically strong, and does not deteriorate substantially under running temperatures and running conditions of an internal-combustion engine. The heat from the cylinder passes through the union from the iron to the copper without substantial obstruction, and the fin, being made of copper (which is almost nine times as good a conductor as iron), permits of ready passage of the heat from the cylinder through the copper. This heat is withdrawn from the copper fins by the cooling air stream, and, owing to the large number of copper fins and their relatively large copper dimensions, the engine has a very large heat dissipating surface which increases its cooling efficiency to a marked degree as compared to iron or steel fins common in this art. The engine may, if desired, operate at far higher compressions than have been common with air-cooled engines heretofore, and a marked economy of operation results from the invention.

While the invention has been described herein more particularly with reference to fins and a finning structure made to cooperate, it will be apparent that the invention in certain of its aspects is not limited to copper but applies to any other suitable high conductive metal from which the fins may appropriately be made.

While the apparatus herein shown and de-

scribed constitutes the preferred embodiment of the invention, it is to be understood that other forms may be adopted and changes made, all coming within the scope of the claims which follow.

What I claim is as follows:

1. An engine comprising a cylinder of ferrous metal, a plurality of fins formed from a sheet of metal folded to provide a series of loops and base portions connecting said loops, the base portions constituting substantially a continuous sheet around the cylinder and being secured to the cylinder over their entire inner surface by permanent metallic union, a jacket surrounding said fins and providing channels between said loops, and means for causing air to flow through said loops and channels. 55

2. The combination with an engine cylinder composed of a metal of low heat conductivity of a series of fins of metal of higher heat conductivity extending longitudinally of said cylinder, the metal of said fins providing a substantially continuous jacket around said cylinder, a casing surrounding said fins and providing, in cooperation with said fins and said jacket, a series of closed channels, and means for supplying a cooling medium to said channels. 60

3. Structure as set forth in claim 2, the said fins and jacket being integral and secured to said cylinder by a union which permits substantially unobstructed flow of heat 70 from the cylinder to the jacket and fins.

In testimony whereof I hereto affix my signature.

CHARLES F. KETTERING.
